CONTROL PANEL FOR A GUITAR OR SIMILAR ARTICLE

Olof Holger Berglund, Alvtdalen, Sweden, assignor to Aktiebolaget Albin Hagstrom, Alvtdalen, Sweden, a joint-stock company of Sweden

Filed May 29, 1959, Ser. No. 56,136

Term of patent 7 years

(Cl. D56—1)

I claim:

The ornamental design for a control panel for a guitar or similar article, substantially as shown.
